[57] **CLAIM**

The ornamental design for a toy weapon, substantially as shown and described.

DESCRIPTION

FIG. 1 is a top plan view of a toy weapon showing our new design;
FIG. 2 is a side elevational view thereof;
FIG. 3 is a front elevation view thereof;
FIG. 4 is a rear elevational view thereof;
FIG. 5 is a bottom plan view thereof; and
FIG. 6 is a side elevation view of the side opposite that shown in FIG. 2.

*Fig. 1.**Fig. 4.**Fig. 2.**Fig. 3.**Fig. 5.**Fig. 6.*
